ATTORNEY

UNITED STATES PATENT OFFICE

WILLIAM C. HEATH, OF BELLOIT, WISCONSIN, ASSIGNOR TO FAIRBANKS, MORSE & CO., OF CHICAGO, ILLINOIS, A CORPORATION OF ILLINOIS

METALLIC CONTAINER

Application filed September 16, 1926. Serial No. 135,822.

My invention relates to improvements in metallic containers, and more particularly to improvements in reinforcing means for such containers and the method of making the same.

The object of my invention is to provide a simpler, more permanent and less expensive reinforcing means for the perimeter or outer edges of metallic containers of substantial size, such as those used for wash tubs, washing machines, and the like.

A further object of my invention is to provide a means for reinforcing the upper edges of a metallic container which may be secured to the container without rivets, bolts, or other securing means apart from the elements constituting the container itself.

A further object of my invention is to provide a reinforcement for the upper edges of a tub or container which will afford sufficient strength and surface to permit the attachment of accessories thereon.

Further objects and advantages of my device will appear from the drawing and the detailed description thereof.

By way of illustration I show my invention as applied to the tub member of a washing machine. The same arrangement may, however, be employed not only around the upper edges of any tub or vat, but may be employed for the purpose of securing together the component parts of such devices. It is sometimes found desirable, in metallic containers adapted to support a substantial load either within or without the container, to use a heavier material for the bottom member than that of which the sides are composed. Such a bottom member may be secured to the sides of the container in a manner substantially like that indicated in the accompanying drawings.

The drawings and the accompanying description deal substantially with the application of my invention to a washing machine tub. This is intended, however, only as an example of a particular application, the same arrangement of parts and method of manufacture being equally adaptable to any device of a similar nature.

It is the usual practice in the manufacture

of washing machine tubs to effect a joint of this sort by riveting the elements together at very close intervals. The result has been unsatisfactory in many cases. The vibration incident to the washing process loosens the rivets. In the case of such a joint below the water line leakage results and the resulting corrosion causes the tub in many cases to be discarded before the operating elements are worn out. Even if all rivets were originally tight, the effect of washing compounds and long exposure to moisture inevitably results in corrosion. I have avoided these difficulties by providing a band member which is preferably cast from an aluminum alloy or other non-rusting material. The method of joining the band member to the sides of the tub results in a joint which is absolutely tight, which is very little affected by vibration and which will have no tendency to tear or snag fabrics in contact therewith as is the case when rivets become loose in bands of ordinary construction.

As a band or joint member I prefer to use a casting of an aluminum alloy having sufficient ductility to permit rolling or bending the sides of the groove without cracking. Any casting of an alloy having the requisite ductility and other characteristics may, however, be used.

Referring to the drawing, Fig. 1 represents a section through the finished band of my invention; Fig. 2 shows its application to a washing machine; and Fig. 3 is a section through a portion of the band before it is subjected to the finishing operation.

Referring by numerals to the drawing, 5 represents a wall of a tub body preferably of sheet metal and provided at the edges with a hem or bead 6. The tub band which is indicated by 8 is preferably made of a reasonably ductile alloy and is bifurcated at its downwardly depending side in such a manner as to provide a recess 9 between a lip 10 and the body portion of the band indicated by 11.

In assembling, the tub band 8 is inserted over the tub body 5 so that hem or bead 6 of the tub wall fits snugly into recess 9 in the tub band. By a single operation lip 10 is rolled down or otherwise crimped securely

over the side wall of the tub. The result is a permanent water-tight joint produced by a single operation and without the extra material and labor formerly incident to a riveted joint. After rolling the joint presents a smooth surface, both inside and outside the container.

While the joint formed in the manner described above is substantially water-tight, a 10 suitable cement or filler 9 may, if desired, be used in special cases between the bead 6 and lip 10 and end 11 of wall 5, particularly where the inside and outside of a container so constructed are subjected to differences in pressure and where a hermetically sealed joint is essential. The lip 10 after being rolled down against the wall 5 may even be roller-welded or seam-welded thereto and the portion 11 of band 8 may also be welded to the wall 5.

20 The band, as shown, has a member curved downward toward the inside of the tub for purposes of drainage. Obviously, either the whole of the top surface of the band, or a portion thereof, may be made flat and may be 25 drilled to receive accessories or appliances, such as wringers, etc.

Although my invention consists largely in the construction and arrangement of parts above described, yet I do not limit my invention to the precise form or construction of parts shown or the several parts thereof, inasmuch as various alterations may be made without changing the scope of my invention, as pointed out in the appended claims.

35 1. In a tub, a beaded sheet metal body portion and a one-piece, cast reinforcing band for said tub, consisting of a ductile alloy element formed separately from said body portion and of angulate section, the depending wall of one of its angles being bifurcated 40 to form an annular pocket receiving the inside and outside of said body-portion at the peripheral margins thereof and the other angular portion extending inwardly of the tub to form an annular shelf, one of the furcations of said first named angle being adapted 45 to be closed upon said margins by pressure, with the beaded portion and margins entirely occupying said annular pocket and forming 50 a substantially tight joint therewith.

55 2. In a tub, or like container, a beaded, sheet metal body portion, a cast flanged band of angulate section, formed of a ductile alloy, the depending wall of one of its angles being bifurcated to form an inverted annular 60 groove, and the material on opposite sides of the groove, and forming the furcations, being pressed into close engagement with the body portion, whereby the groove is entirely occupied by the beaded portion of the body, and the band secured to the body portion, and another angle portion extending inwardly of the tub to form a shelf about the tub opening.

65 3. In a washing machine tub, a sheet metal body portion, and a cast reinforcing band of

a ductile aluminum alloy, forming a shelf for said tub, about the tub opening; said band being bifurcated to engage the inside and outside of said body portion at a peripheral margin thereof, the band and body portion being separately formed, and pressed into mutual engagement.

4. In a washing machine tub, the combination of a sheet metal body and a reinforcing member, formed of an aluminum alloy, said reinforcing member being attached at a peripheral margin of said body and comprising a portion extending inwardly of said body and a portion integral therewith and at an angle thereto extending downwardly along said body, said downwardly extending portion being bifurcated at the extremity where it engages said body, the bifurcated portion being rolled to embrace said body at its peripheral margin to form a substantially tight joint.

WILLIAM C. HEATH.
